FUSE

Filed Nov. 30, 1925.

UNITED STATES PATENT OFFICE

ALWIN G. STEINMAYER, OF MILWAUKEE, WISCONSIN, ASSIGNOR, BY MESNE ASSIGNMENTS, TO LINE MATERIAL COMPANY, A CORPORATION OF DELAWARE

FUSE

Application filed November 30, 1925. Serial No. 72,162.

It is a general object of this invention to simplify and improve the construction of fuses of that type especially designed for interrupting high-voltage circuits upon the occurrence of excessive overloads.

Another object of this invention resides in the provision of an improved fuse construction, wherein the terminal members with which the fuse carrying terminal engaging elements are engageable are mounted on the inner ends of the lead-in insulators, whereby but two insulating members are required in the entire construction.

A further object of this invention resides in the provision of an improved device of the character described, wherein the lead-in insulators and terminal members are fixed upon a single mounting plate which is readily removably secured to the rear wall of the fuse housing to facilitate their ready removal as a single unit.

This invention has as a still further object the provision of an improved and simplified fuse unit in which the fuse element is enclosed throughout its entire length and the gases generated by the volatilization of the elements vented outwardly of the housing.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

The single view illustrates a fuse switch construction embodying my invention, the housing being in vertical section and parts of the fuse proper being broken away.

In the drawing, the numeral 5 designates a box or housing having apertures 6 in its rear wall 7, through which project tubular lead-in

insulators 8 fixed, as at 9 in a mounting plate 10, secured to the box rear wall by bolts 11.

The insulators 8 have terminal members 12 mounted on their inner ends that carry switch terminal members 13 of the clip type adapted to receive the terminal engaging elements or contacts 14 and 15 of a fuse 16. The terminals 12 have binding screws or other means 17 for electrically connecting the lines 18, of a circuit in which the device is incorporated.

The mounting 10 is made of any suitable material and is flanged, as at 19, where it receives the insulators 8, and the flanges have recesses or grooves 20 in their inner surfaces to provide a firm anchor for the cement or other means 9 employed to secure the insulators in place. As will be readily apparent, the mounting 10 and the insulators and terminals carried thereby may be bodily removed from the housing by removing the bolts 11, moving the plate 10 from the wall 7 until the flanges 19 disengage the openings 6, shifting the mounting longitudinally to align one terminal 13 with its adjacent opening, then withdrawing the aligned terminal from its opening 6 and shifting the mounting longitudinally in an opposite direction to align the other terminal with its opening and then withdrawing the same. This construction greatly simplifies the construction of the housing and facilitates repairs or replacement of the parts.

The fuse 16 consists of an elongated open ended tube 21 of suitable insulating material having one end 22 externally threaded and secured within the terminal engaging element 14, the other end of the tube being passed through and extended beyond the other terminal engaging element 15. The threads 22 form the means for mounting the element 14 on the tube 21, and the element 15 is fixed on the tube by binding bolts 23 adapted to draw the split ends 24 of the element thereabout. The element 14 has a bore 25 in its end which is normally closed by a removable cap 26 threaded on a boss 27 formed on the element, the cap 26 providing means for clamping the upper end 28 of a fuse element 29 in electrical connection with the terminal element 14. The fuse element 29 has a re-

duced cross-sectional area 30 adjacent its end 28 and extends through the length of the tube 16 and outwardly of its lower end and its end portion 31 is folded back along the exterior of the tube and clamped within the channel 32 of the enlarged or flanged portion 33 of the element 15 by a sleeve or collar 34 threaded into flange 33.

The lower end of the tube 21 projecting beyond the terminal element 15 extends below the bottom 35 of the box through the opening 36 thereof to permit the venting of the tube outwardly of the box. A second tube 37 surrounds the extended end of the tube 16 and the end portion 31 of the fuse and is fixed to the sleeve or collar 34 by threads or other means 38, the tube 37 having its lower end extended beyond the lower end of the other tube.

The fuse as a unit is mounted on a block or other means 39, carried by a door 40, closing the outer face of the box so that when the door is opened, the fuse unit is carried therewith to disengage the elements 14 and 15 from the terminals 12 and 13. The block 39 is connected with the door by a wing nut arrangement 41 so that the door 40 may be opened without carrying the fuse unit therewith.

30 What I claim as my invention is:

1. In an electrical appliance of the character described, a housing having a plurality of spaced apertures in one wall thereof, a plate member removably secured to the apertured wall of the housing, and having openings therein registering with said apertures, inwardly struck flanges surrounding the plate member openings and adapted to fit within the housing apertures, and lead-in insulators fixed in the openings of the plate member and adapted to have their inner ends located within the housing interior and their outer ends extended outwardly thereof.

2. In an electrical appliance of the character described, a housing having a plurality of spaced apertures in one wall thereof, a plate member removably secured to the apertured wall of the housing and having openings therein registering with said apertures, inwardly struck flanges surrounding the plate member openings and adapted to fit within the box apertures, lead-in insulators secured in the openings of the plate member and adapted to have their inner ends located within the housing interior and their outer ends extended outwardly thereof, and terminal elements fixed to the inner ends of the lead-in insulators.

3. In an electrical appliance of the character described, a housing having a plurality of spaced apertures in one wall thereof, a plate member having openings therein registering with said apertures, means removably securing the plate member to the apertured wall of the housing, lead-in insulators mounted in

the openings of the plate member and projected into the housing through the apertures therein, and terminal members fixed to the inner ends of the lead-in insulators and projected therebeyond in opposite directions to extend beyond the opposed diametric points of the housing apertures, the apertures in the housing wall being greater than the diameter of the lead-in insulators whereby the plate carrying the insulators may be shifted in one direction after its securing means has been removed to align one terminal member with its wall aperture and then shifted in the opposite direction to align the other terminal member with its wall aperture, whereby to facilitate the removal of the plate, lead-in insulators and terminal members as an entirety.

4. In combination with a fuse having contacts, a housing having an apertured wall, a plate member removably secured to the apertured wall and having spaced openings therein, tubular lead-in insulators fixed in the plate member openings with their inner ends projected through the apertured wall into the housing and their outer ends extended outwardly from the plate member, and terminal members fixed to the inner ends of the tubular lead-in insulators, said terminal members being adapted to engage the fuse contacts.

5. In combination with a fuse having contacts, a housing, terminals within the housing adapted to engage the fuse contacts to support the fuse and be electrically bridged thereby, and means detachably connected with the housing and having both terminals rigidly connected therewith in predetermined fixed relation to each other to insure proper electrical contact between the fuse contacts and the terminals, whereby the terminals and their mounting means form a unit substantially independent of the housing to permit the terminals to be removed from the housing without disturbing their fixed relationship.

6. In combination with a fuse having contacts, a housing, terminals within the housing adapted to engage the fuse contacts to support the fuse and be electrically bridged thereby, and means mounting the terminals in predetermined fixed relation to each other including tubular lead-in insulators to which the terminals are secured and through which conductors enter the housing to be connected with the terminals, and means rigidly connecting the insulators, said means being detachably connected with the housing whereby the terminals and their mounting means form a unit substantially independent of the housing and the terminals are removable from the housing without disturbing their fixed relationship.

In testimony whereof I affix my signature.

ALWIN G. STEINMAYER.
